PLASTIC COATED SHEET MATERIAL

Richard A. Mazur, McFarland, Wis., assignor to Uniroyal,
Inc., a corporation of New Jersey

Filed Jan. 14, 1966, Ser. No. 672

Term of patent 14 years

(Cl. D87—3)

Ex-1

FIG. 2

FIG. 1 is a plan view of a plastic coated sheet material showing my new design; and

FIG. 2 is an enlarged fragmentary view showing the design substantially in full scale.

A single repeat of the design is enclosed within the quadrilateral figure bounded by the broken-lines in FIG. 1 of the drawing.

I claim:

The ornamental design for a plastic coated sheet material, as shown and described.
